UNITED STATES PATENT OFFICE.

EMILIE ALPHONSE OMER VIEL, OF PARIS, FRANCE.

FURNACE FOR EFFECTING FUSION FOR REFINING.

No. 895,519.

Specification of Letters Patent.

Patented Aug. 11, 1908.

Application filed November 19, 1907. Serial No. 402,883.

To all whom it may concern:

Be it known that I, EMILIE ALPHONSE OMER VIEL, citizen of the Republic of France, residing at 9 Rue Pillet-Will, Paris, France, have invented a new and useful Improved Furnace for Effecting Fusion for Refining, of which the following is a specification.

The present invention has for its object an improved furnace for effecting fusion or for refining.

The furnace is formed by the temporary or permanent combination or juxtaposition of two independent elements; a crucible of suitable form either fixed, or capable of being rotated or tipped, and having the usual orifices for charging and discharging, and in addition one or more orifices for the admission of an electric arc produced outside thereof by the second element of the furnace.

The arc produced externally is blown into the interior of the oppositely situated crucible by a suitable blowing contrivance, preferably by electro-magnets of variable position and inclination.

One form of construction of the invention is as a representative example shown on the annexed drawings, in which:

Figure 1 is a sectional longitudinal elevation; Fig. 2 is a partial end elevation. Fig. 3 is a plan and:—Fig. 4 shows diagrammatically a modified arrangement.

The furnace comprises a crucible *g* lined with refractory material (lime and an oxid of the metal to be refined). This crucible preferably in the form of a drum is inclosed in a metallic casing *n* provided with a toothed wheel *o*, and a grooved ring *p* with which two rotatable spheres engage forming tipping supports carried between two bearings *q*, themselves supported by standards *s* on a carriage *l*. This latter carries also a toothed wheel *h* gearing with the wheel *o*, and mounted on a shaft *t*, to which is secured a driving pulley *u*.

The crucible has two orifices *m* and *k* for charging and discharging. The side orifice *m*, owing to the mobility of the carriage *l* mounted on the rails *v*, is adapted to be brought into proximity with the fixed contrivance, adapted to produce an electric arc. This latter contrivance comprises two electrodes *a* *a* of which the supports *c* can each slide in a guide *d* carried on an insulating framework (*e* *e*), the advance or withdrawal of the supports being effected by means of a screw *w* operated by a crank *x*. The elec-

trodes, whose position, inclination, and distance apart are regulated according to the purpose and as desired can, while in use, be brought nearer to or withdrawn further from the orifice *m*. The arc which springs between them will be blown, through the orifice *m* to the interior of the crucible, by means of an electro-magnetic contrivance of known construction comprising for example for the employment of a continuous current a core of horse-shoe shape composed of non-magnetic material, on one of the branches of which is mounted a solenoid *b*, of which one of the extremities is connected to a rheostat, and the other to a current supply. An electro-magnet, for the employment of an alternating current, will have the ordinary necessary modifications.

The core of the electro-magnetic blower is arranged to be cooled by a stream of water *z*, to avoid the resistance created by heating. The rheostat *r* allows of regulation at will of the power of the arc. By rotating the crucible *g* by means of the transmission gear *u*—*t*—*h*—*o*, or by inclining it on its supporting rollers *j*, the point of impact of the arc blown from the exterior can be varied during the operation, and the molten mass can thus be stirred. The blowing of the arc produced externally causes a draft of atmospheric air towards the interior of the crucible, and this natural current of air can be reinforced if desired, by a forced draft produced by a ventilator.

As shown diagrammatically in Fig. 4, a crucible open at the top could be employed, and the external arc arranged above this opening, the arc being then directed towards the interior by the electro-magnetic blowing contrivance. The crucible would comprise two side orifices *1*, *2*, for the inlet of air and outlet of gases of combustion.

As has been said above in the apparatus described which is really an electric Bessemer converter, the mounting of the independent external electrodes will vary according to the form and use of the oppositely situated crucible, in some cases the electrodes being inclined as shown in Fig. 1 and in others vertical as shown in Fig. 4.

I claim:

1. In a furnace of the character described, the combination with a suitably orificed crucible, of means external to the furnace and crucible for producing an electric arc adapted to be blown into said crucible.

2. In a furnace of the character described, the combination with a suitably orificed crucible, of means for producing an electric arc arranged externally to the furnace and crucible, and means for blowing the arc through the orifices into the crucible.
3. In a furnace of the character described, the combination with a suitably orificed crucible, of means external thereto for producing an electric arc adapted to be blown into said crucible, and means for varying the positions of said crucible and said arc producing means relatively to each other.
4. In a furnace of the character described, the combination with a suitably orificed crucible, of means for rotating and tilting the same, and means external to the crucible for producing an electric arc adapted to be blown into the crucible.
5. In a furnace of the character described, the combination with a suitably orificed crucible, of means for rotating and tilting the same, means external to the crucible for producing an electric arc, and means for blowing the electric arc through the orifices into the crucible.
6. In a furnace of the character described,

the combination with a suitably orificed crucible, of means external thereto for producing an arc adapted to be blown into the crucible, and means for regulating the position of said arc producing means.

7. In a furnace of the character described, the combination with a suitably orificed crucible, of electrodes external thereto for producing an arc adapted to blow into the crucible, and means for adjusting the position, inclination and distance apart of said electrodes.

8. In a furnace of the character described, the combination with a suitably orificed crucible, of means external thereto for producing an electric arc adapted to be blown into the crucible, and means for regulating at will the power of the arc produced by said arc producing means.

In testimony whereof I have signed my name to this specification in the presence of two subscribing witnesses.

EMILIEN ALPHONSE OMER VIEL.
